UNITED STATES PATENT OFFICE.

JOSEPH A. WILLIAMS, OF CLEVELAND, OHIO.

DYNAMO-ELECTRIC MACHINE.

No. 926,225.

Specification of Letters Patent.

Patented June 29, 1909.

Application filed September 13, 1906. Serial No. 334,400.

To all whom it may concern:

Be it known that I, JOSEPH A. WILLIAMS, a citizen of the United States, residing at Cleveland, in the county of Cuyahoga and State of Ohio, have invented a certain new and useful Improvement in Dynamo-Electric Machines, of which the following is a full, clear, and exact description.

The object of the present invention is to provide an improved form of generator, designed particularly for use in connection with explosive engines to produce ignition sparks, although it is clear that the invention is capable of much wider application.

15 A further object is to produce a generator which, in addition to being simple in construction, is of a stable character and is capable of producing an increased number of alternations of flow of the magnetic lines of force for each revolution, and consequently, many alternations of the induced current in the armature winding.

20 The invention involves the combination, with the pole pieces and their magnets, of an armature, consisting of windings and a core made of magnetics material passing through said windings and mounted so as to rotate upon an axis which is substantially coincident with the axis of the axis of the 25 windings, said core being provided with a plurality of wings which are arranged one-half on one side and the other half on the opposite side of the armature windings and are so disposed that when any wing on one 30 side of said windings is in juxtaposition with one pole, a wing on the other side of said windings is in juxtaposition with a pole of opposite sign.

35 The invention further involves an electric generator having the characteristics referred to when the armature windings are upon a non-rotatable spool, and it further involves details of construction as shown in the drawing and hereinafter described and claimed.

40 In the drawings, Figure 1 is a side elevation of a machine embodying the invention, the windings being shown partly in section. Fig. 2 is a top plan view of the machine shown in Fig. 1, one of the magnets being broken away. Fig. 3 is an end elevation, one of the 45 magnets being broken away. Fig. 4 is a detail sectional view taken on the line 4—4 of Fig. 1. Fig. 5 is a sectional view taken on the line 5—5 of Fig. 1.

50 Referring to the drawings, N and S represent respectively, the north and south pole

pieces of the magnets A' A², which magnets may be permanent magnets or electro-magnets, as desired. The pole pieces are so disposed that the pieces at the opposite ends 60 of the same side of the machine are of opposite polarity and the pieces on the opposite sides of the same end are of opposite polarity. The faces of said pole pieces are curved about the axis of the core D as a 65 center and the centers of said pole faces on opposite sides at the same end are substantially 90° apart, and the centers of the faces on the same side are practically in a line parallel with the axis of the core D. 70

D represents the armature core and E the armature windings, said windings consisting of an insulating spool and wire coils wound thereon. The armature core is rotatably mounted between the curved faces of 75 the pole pieces and upon an axis which is coincident with the axis of curvature of said pole pieces, and said core passes through the armature windings, that is to say, through the spool and the wire coils thereon so that 80 its axis of rotation is substantially coincident with the axis of said windings. C represents the bearings in which said armature core is mounted.

In the construction shown, the windings, 85 that is to say, the spool and the coils thereon, are stationary, the spool being fixed to a suitable support C'. It is not, however, of the essence of the broad invention that these windings shall be non-rotatable, although it 90 is a desired feature of construction.

The core, which must be made of magnetic material, preferably soft iron, is provided with four radiating wings D' D² D³ and D⁴. The wings D' D² are at one end of the spool 95 and the other two wings, namely, D³ D⁴ are at the other end thereof. The wings D' and D³ extend in the same direction in the same diametrical plane, while the wings D² and D⁴ extend in the diametrically opposite direction, and, therefore, in the same diametrical plane. 100

The pole pieces and wings being arranged as described, it is evident that when one of the wings, as for example the wing D', is in 105 juxtaposition to the face of one pole piece, the end of the wing D³ which extends in the same plane and in the same direction from the core but at the opposite end thereof, will be in juxtaposition to the face of another 110 pole piece of the opposite sign. The magnetic lines of force flowing from the north

5 pole piece would enter one wing D' , for example, and flow along the core and through the windings and, out of the wing D^3 to the south pole piece, thereby inducing a current flow in one direction through the wire of the coils.

As the core continues to rotate, it next 10 brings the wing D^4 in juxtaposition to the second north pole piece which will be at the opposite end from the north pole piece first mentioned and the wing D^2 will be brought into juxtaposition to the second south pole piece which lies at the end opposite to that at which the first mentioned south pole piece 15 is located, whereupon the magnetic lines of force will enter said wing D^4 and flow along the core and thence through the wing D^2 to a south pole piece, thereby going through the windings in the opposite direction and inducing in the wire of the coils a current 20 flow in the direction which is opposite to that first referred to. The device shown, has, therefore, a great advantage over other magneto-electro machines used for this purpose, especially such machines as are used 25 upon automobiles, because such other devices do not become sufficiently active to produce the desired result until they come into rapid rotation, and therefore, it is usually necessary to provide an auxiliary device 30

of some sort as a dry battery to produce the igniting sparks necessary to put the engine in operation.

Having thus described my invention, I claim:

In a magneto-electric machine, the combination of a spool on which are armature windings, and a rotatable core passed axially through said spool and having, at one end of the spool, two diametrically opposed projecting wings, and having at the other end of said spool two opposed projecting wings lying in the same diametrical plane with the two first mentioned wings, with a pair of magnets having pole pieces whose faces are 45 concentric with the axis of said core and lie outside the radial length of the said wings but closely adjacent thereto, inclosing the path of movement of the wings beneath the same, which pieces are of opposite polarity 50 at the opposite ends of the same side of the machine and of opposite polarity on the opposite sides of the same end of the machine.

In testimony whereof, I hereunto affix my 55 signature in the presence of two witnesses.

JOSEPH A. WILLIAMS.

Witnesses:

J. M. WOODWARD,

E. B. GILCHREST.
